TOOL FEEDING DEVICE

Eric C. Brodin, Jenkintown, Pa., assignor to SKF Industries, Inc., Philadelphia, Pa., a corporation of Delaware

Application May 23, 1945, Serial No. 595,312

7 Claims. (Cl. 51—166)

1

This invention relates to means for relatively feeding the cutting or grinding elements of machine tools and the work, and one object of the invention is to provide a feed device affording a higher degree of precision than can be obtained by the prior conventional feed devices.

It is customary to mount cutting and grinding tools on posts or heads which are movable on suitable guide means to and from the work. This method of feeding the tool to the work, while in general satisfactory, tends to fail when small tolerances are involved, and particularly when it is necessary to reproduce on a quantity basis pieces having highly precise dimensions. The aforescribed conventional feed devices are frequently incapable of relocating the tool with sufficient accuracy in a given operating position as required when passing rapidly from one piece to another. This is due apparently to variation in friction between the traversible tool support and its guide.

It is a primary object of this invention to provide a feed device which will eliminate these variables and which will thereby afford a feed of relatively high precision.

More specifically, an object of the invention is to provide a feed device wherein the advance of the tool to the work may be effected without movement of the tool support as a whole and in a manner to substantially eliminate variations arising from frictional effects.

The invention will be more readily understood by reference to the attached drawings wherein:

Fig. 1 is a side view of a holder for a grinding wheel wherein provision is made for feeding the wheel to the work in accordance with the principle of the invention;

Fig. 2 is a somewhat enlarged fragmentary side and partial sectional view of a holder illustrating a modification within the scope of the invention;

Figs. 3, 4, and 5 are sectional views of tool holders illustrating still further applications of the inventive principle, and

Fig. 6 is a side elevational view illustrating another embodiment within the scope of the invention.

The embodiment of the invention illustrated in Fig. 1 of the drawings comprises a holder 1 wherein is journaled a grinding wheel 2. This wheel may be rotated in the holder by any conventional means, and since the wheel rotating devices form no immediate part of the invention, the elements thereof have not been included in the drawings. The holder 1 departs

from the conventional in having therein a deep slot 3 which forms a relatively narrow neck portion 4 between the front terminal end 5 of the holder, wherein the wheel 2 is journaled, and the body 6 of the holder. Threaded into an upstanding portion 7 of the body 6 is a feed screw 8, the inner end of which traverses the outer end of the slot 3 and engages the side of the end portion 5. The other end of the screw is provided, in the present instance, with a suitable handle 9 by means of which the screw may be turned so as to exert pressure upon the end portion 5 of the holder, to thereby spring the relatively narrow neck portion 4, and to displace the grinding wheel 2 with respect to the body of the holder.

Assuming now that the holder 1 is rigidly supported in the machine tool in a position wherein the grinding wheel 2 may contact the work, or lie in close proximity thereto, it is apparent that by turning the screw 8, the wheel 2 may be advanced or fed into or against the work. The feeding movement of the wheel 2 is effected entirely by flexure of the material of the holder 1 in the neck 4. Since the elasticity of steel or other metal from which the holder 1 may be formed is a constant, a given flexure of the holder will advance the tool always to the same extent. If, therefore, means be provided, such, for example, as a dial in association with the screw for indicating the positions of the latter in the holder, assurance is afforded that in any fixed position of the holder 1, a given position of the screw will always correspond to a given position of the grinding wheel 2 with respect to the work. The device, therefore, affords a means for moving the wheel 2 exactly to the same working position with respect to any number of like work pieces passed successively through the machine.

In Fig. 2 the construction of the holder, designated in this instance by the reference numeral 19, is similar to that described above and illustrated in Fig. 1, with the exception that in this instance the feeding of the grinding wheel 21 is effected through the medium of an hydraulic means instead of by the mechanical device of the previously described embodiment. In this instance, an expandable diaphragm member 23 is mounted in the outer end of the slot 23 in a manner such that when hydraulic pressure is applied thereto, as by way of a duct 29, the resulting expansive pressure of the member between the sides of the slot 23 will cause a flexure of the holder 10 in the neck portion 24 thereof in the manner described above.

In Fig. 3 the holder 39 is formed, in effect, with a plurality of slots 33 arranged serially, and each of the slots is provided at its outer end with an expansible diaphragm device 38 connected to a common hydraulic system which may be designated generally by the reference numeral 39. Application of hydraulic pressure to the elements 38 results in a flexing of the metal of the holder 39 in the several neck portions 34 with the result that the grinding wheel 32 is displaced in an obvious manner. This embodiment of the invention differs from those illustrated in Figs. 1 and 2 in that it affords a substantially straight line feeding movement of the grinding wheel 32 as indicated by the arrow A², as distinct from the arcuate movements of the grinding wheels 2 and 12 in the embodiments of Figs. 1 and 2 respectively as indicated by the curved arrows A and A¹ of those figures. In this case also, it is apparent that a relatively small expansion of the elements 38 will effect a relatively great movement of the grinding wheel 32, the movement of the wheel corresponding to the sum of the expansion movements of the individual elements 38.

The holder shown in Fig. 4 is essentially the same as the holder 30 illustrated in Fig. 3 with the exception that in this instance, a single hydraulic element 48 is employed in lieu of the several such elements 38 of the previously described embodiment. The element 48 is located to the rear of the serpentine formation which produces the slots 43, 43, and the flexible neck portions 44; and a rod 49 extends through apertures in the walls of the nearer slots 43 and is secured in the end portion 45 of the holder which journals the grinding wheel 42. It is apparent that in this case expansion of the element 48 will advance the wheel 42 by flexure of both of the neck portions 44. In this case also the movement of the grinding wheel is a linear one, as indicated by the arrow A³.

In the embodiment of the invention illustrated in Fig. 5, the grinding wheel 52 is journaled in a block 53, which block is supported on upright parallel flexible arms 54, 54. These arms are secured at the bottom to the body 55 of the tool holder. The holder also comprises an upwardly extending portion 56 in which is threaded a feed screw 57, the inner end of which bears against the side of one of the flexible members 54 at one side of the block 53. Advancement of the screw 57 will effect a flexure of the arms 54 and a feeding movement of the wheel 52 in the direction of the arrow A⁴. The arms 54 being resilient will return to their original positions when the screw 57 is backed away in the upright 56.

It will be understood that the aforescribed devices may be used to feed the work relative to the tool, instead of the tool into the work, and that such reversal is contemplated as falling within the scope of the invention. In Fig. 6, for example, the work 58 is shown as supported in a holder 59 comprising a typical flexible portion 60, said portion connecting the two parts 61 and 62 of the holder and providing for relative displacement of these parts in the manner previously described. The work 58 is held in the part 61, and a screw 63 threaded in the relatively fixed part 62 provides for displacement of the part 61 and of the work piece in a manner to feed the work against a grinding wheel 64, the latter being mounted in a structure 65. Obviously, hydraulic or other suitable means may be used in lieu of the screw 63 to effect the feeding of the work piece.

I claim:

1. In a tool feeding device, a holder having a recess terminating at the bottom in a resilient portion of the holder, means for mounting a tool on the holder at one side of said recess, and a fluid pressure system including a fluid-actuated expandable element confined in and between the sides of said recess and through which accurately regulated pressure may be applied to said sides to flex said resilient portion and to effect a displacement of the tool with respect to that part of the holder on the other side of the recess.
2. In a tool feeding device, a holder having a series of more or less parallel recesses extending inwardly from opposite sides of the holder and each terminating at the bottom in a resilient portion of the holder, means at one end of said series for mounting a tool on the holder, and means operatively associated with the holder at the other end of said series for exerting pressure tending to flex the said resilient portions all in the same direction to thereby displace the tool mounting with respect to that part of the holder at the said opposite end of the series.
3. In a tool feeding device, a holder having a series of more or less parallel recesses extending inwardly from opposite sides of the holder and each terminating at the bottom in a resilient portion of the holder, means at one end of said series for mounting the tool on the holder, and means for exerting pressure to simultaneously flex the resilient portions unidirectionally to displace the tool mounting with respect to that part of the holder at the other end of said series.
4. In a tool feeding device, a holder having a series of more or less parallel recesses extending inwardly from opposite sides of the holder and each terminating at the bottom in a resilient portion of the holder, means for exerting pressure to vary the distance between the portions of the holder on opposite sides of said series of recesses by flexure of said resilient portions, and means on one of said side portions for mounting a tool on said holder.
5. A tool feeding device according to claim 3 wherein the said pressure-exerting means is fluid-actuated.
6. A tool feeding device according to claim 3 wherein the said pressure-exerting means includes at least one fluid-actuated expandable element.
7. In a device for effecting relative feeding movements between tool and work elements, a holder having a free end portion formed by a recess terminating at the bottom in a resilient portion of the holder, means for mounting one of said elements on the free end portion of the holder at one side of said recess, and means for exerting pressure on the holder at points on opposite sides of said recess so as to flex said resilient portion and to effect a displacement of said free end portion and the mounted element with respect to that part of the holder on the other side of the recess, said pressure means operating continuously to control flexure of the said resilient portion, and said free end portion being otherwise unsupported against the thrusts resulting from reaction of the said tool and work elements and being free for displacement by action either of said pressure means or of the said resilient portion of the holder.
